(57) **CLAIM**

The ornamental design for a cup lid, as shown and described.

DESCRIPTION

FIG. 1 is a front and bottom perspective view thereof;
FIG. 2 is an exploded rear and top perspective view thereof;
FIG. 3 is a rear and top perspective view of a first piece of
the cup lid, shown independently to show aspects of the
design not visible when combined;
FIG. 4 is a front and bottom perspective view thereof;
FIG. 5 is a front elevation view thereof;
FIG. 6 is a rear elevation view thereof;
FIG. 7 is a left side elevation view thereof;
FIG. 8 is a right side elevation view thereof;
FIG. 9 is a top plan view thereof;
FIG. 10 is a bottom plan view thereof;
FIG. 11 is a rear and top perspective view of a second piece
of the cup lid, shown independently to show aspects of the
design not visible when combined;
FIG. 12 is a front and bottom perspective view thereof;
FIG. 13 is a front elevation view thereof;
FIG. 14 is a rear elevation view thereof;
FIG. 15 is a left side elevation view thereof;
FIG. 16 is a right side elevation view thereof;
FIG. 17 is a top plan view thereof;
FIG. 18 is a bottom plan view thereof;
FIG. 19 is a rear and top perspective view of a third piece
of the cup lid, shown independently to show aspects of the
design not visible when combined;
FIG. 20 is a front and bottom perspective view thereof;
FIG. 21 is a front elevation view thereof;
FIG. 22 is a rear elevation view thereof;
FIG. 23 is a left side elevation view thereof;
FIG. 24 is a right side elevation view thereof;
FIG. 25 is a top plan view thereof; and,
FIG. 26 is a bottom plan view thereof.

The broken lines in the figures illustrate portions of the cup
lid that form no part of the claimed design.
